UNITED STATES PATENT OFFICE.

FRANK CLARKE, OF WACO, TEXAS.

ENVELOPE-CLOSING MEANS.

Application filed April 30, 1921. Serial No. 465,677.

To all whom it may concern:

Be it known that I, FRANK CLARKE, a citizen of the United States, residing at Waco, in the county of McLennan and State 5 of Texas, have invented new and useful Improvements in Envelope-Closing Means, of which the following is a specification.

This invention relates to a device for closing envelopes, the general object of the 10 invention being to provide means for turning the flap over upon the body of the envelope and applying pressure to the flap after it has been turned over to cause the adhesive to adhere to the body, such means 15 being associated with suitable conveying means.

Another object of the invention is to provide a part of the folding means with a knife edge for giving the flap its initial turning 20 movement.

This invention also consists in certain other features of construction and in the combination and arrangement of the several parts, to be hereinafter fully described, 25 illustrated in the accompanying drawings and specifically pointed out in the appended claims.

In describing my invention in detail, reference will be had to the accompanying 30 drawings wherein like characters denote like or corresponding parts throughout the several views, and in which:—

Figure 1 is a plan view showing the folding means and a part of the conveying belt. 35 Figure 2 is a section on line 2—2 of Figure 1.

Figure 3 is a section on line 3—3 of Figure 2.

Figure 4 is a section on line 4—4 of Figure 2.

Figure 5 is a perspective view of the front end of the folding member showing its knife edge.

In these views 1 indicates a part of the 45 conveyor frame and 2 a part of the conveyor belt which is provided with the transverse strips 3 at its front edge, which form brackets for receiving the envelopes, one of which is shown in dotted lines in Figure 1.

50 The folding means consists of a folding member 4 and a holding member 5, the member 4 being supported by the brackets 6 which are secured to a part of frame 1 and the holding member 5 is supported by the

bracket 7 which is also connected to a part 55 of the frame. Member 4 is formed from an angle bar, the brackets 6 being secured to the horizontal flange. The front end of the horizontal flange is of large dimensions, as shown at 8, and the vertical flange is 60 curved outwardly across this enlargement, as shown at 9, this flange being slightly inclined at its outer end, as shown in Figures 1 and 5. The inner or forward corner of part 8 is provided with a knife edge, as 65 shown at 10, so that the flap of the envelope will ride over the same and thus be given its initial lifting movement. Adjacent the center of the member 4 the vertical flange is twisted, as at 11 so as to locate the rear part 70 of this flange at an incline, as shown at 12 which gradually merges into the horizontal flanges at the extreme end of the member. It will thus be seen that as the flap rides over the knife edge it will be lifted slightly 75 and then as it strikes the curved part 9 of the vertical flange it will be moved to a vertical position or a position at right angles to the body, and upon the continued movement of the belt, said flap will strike the 80 twisted part 11 so that it will be moved downwardly towards the body of the envelope and then as it moves along the part 12 it will gradually be forced upon the 85 body. In order to press the flap firmly upon the body to cause the adhesive thereon to stick to the body I provide a member 13 which is hinged to the rear end of member 4 and is pressed upon the belt by the spring 14. Thus as the envelope leaves the folding device its flap will encounter this member 13 which will apply pressure upon the 90 same and thus cause it to adhere to the body.

The holding member 5 is also formed of a channel bar with the bracket 7 secured to the horizontal flange thereof. This flange is curved upwardly at the front end, as shown at 15, for facilitating the envelope passing under the holder. This member is so located that the crease at the junction 100 of the flap with the body will come along the inner edge of the horizontal flange of the member. At the rear the member 5 is cut away to leave the reduced part 16 which is located under the part 12 of member 4 105 so as to prevent the holding member from coming in contact with the adhesive coated surface of the flap of the envelope. This

member 5 serves the purpose of holding the envelope upon the belt and acts as a straight edge about which the flap is turned.

As the envelope moves under the holding member of the folding device it will be firmly held in position with the flap ready to be acted upon by the folding member. The knife edge of the folding member will cause the flap to move off the conveyor belt and the curved part of the vertical flange of said member will move the flap into upright position and then the twister part will move it downwardly towards the body of the envelope, the rear part 12 finishing the folding operation and the spring member 13 will apply pressure upon the flap and cause the flap to adhere to the body.

The device is mainly intended for use upon envelopes with narrow flaps, such, for example, as envelopes for containing seeds, though it will of course be understood that the device could be made for use upon other kinds of envelopes with but slight change.

The belt may travel upon rollers, such as shown at 17 and I locate one of these rollers under the member 13 to take the pressure thereof.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. An envelope closing device comprising a conveyor, a holding member for holding the envelope upon the conveyor and a folding member associated with the holding member and comprising a curved and twisted flange for folding the flap upon the envelope, the front end of said folding member being flat and provided with a knife edge for initially lifting the flap. 40 45

2. An apparatus of the class described comprising a conveyor, holding means for holding the envelopes upon the conveyor, a folder associated with the holding means and comprising a flat front end having its inner corner provided with a knife edge and an upwardly extending flange having its front end curved outwardly across the flat part and an intermediate part twisted outwardly and downwardly and its rear part 50 55 being substantially flat.

3. A device of the class described comprising a conveyor belt, a holding member having its forward end curving upwardly and its rear part cut away to leave a reduced flat part, a folding member associated with the holding member, said folding member having a knife edge at its front end and an upwardly extending flange having an outwardly curved front edge and a 60 65 downwardly and outwardly intermediate twisted part and a spring actuated hinged member at the rear end of the folding means.

In testimony whereof I affix my signature. 70
FRANK CLARKE.
